UNITED STATES PATENT OFFICE

MELVIN MCKINLEY, OF COSHOCTON, OHIO, ASSIGNOR TO THE COSHOCTON GLOVE CO., OF COSHOCTON, OHIO, A CORPORATION OF OHIO

GLOVE-BLANK FORMING

Application filed June 25, 1927. Serial No. 201,341.

This invention relates to features of dies and economy in cutting of sheet metal.

This invention has utility when incorporated for the manufacture of gloves, especially from cloth involving simultaneously cutting therefrom of a plurality of blanks transversely of a plurality of thicknesses of the cloth.

Referring to the drawings:

10 Fig. 1 is a plan view of a group or gang die designed for effecting economy in cutting hereunder;

Fig. 2 is a view, with parts broken away, showing a glove as assembled from blanks 15 as formed by the die of Fig. 1;

Fig. 3 is a section on the line III—III, Fig. 2; and

Fig. 4 is a section on the line IV—IV, Fig. 2.

20 Strip 1 of cloth, say muslin, may be overlaid for a plurality of plies, say forty-eight thicknesses, for producing twenty-four pairs of glove blanks in a cutting depth, and be operated thereon under the invention hereinafter by a group or gang die approximating 25 the full width of the strip 1 of cloth. In carrying out the invention hereunder, saving of cloth is effected with maintenance of glove size and glove utility.

30 The glove blank die is shown as having palm portion 2 extending to widened wrist portion 3. Intermediate the extent of this wrist portion 3 is thumb 4 having side 5 of less than full form. Remote from this 35 thumb 4 and beyond the narrower palm portion 2 are finger portions 6, 7, 8, 9. The portion shown as the index or first finger 6 has lateral extension 10 for the index finger back, with widened offset 11 therefrom extending toward the palm to inward offset or narrowing portion 12.

From the portion 11 beyond the portion 12, there is widening portion 13 of the wrist portion 3. The opposite side of this 45 blank, has from the little finger 9, outer edge 14 provided with offset or narrowing portion 15 to straight portion 16 terminating in widening portion 17 extending to wrist widened portion 18 opposite the wrist 50 widened portion 13.

In the closing of these blanks in the single die unit as shown in Fig. 1 for a group assembly, the adjacent blank outlines are oppositely disposed in the transverse series for line interfitting between the index finger forms of adjacent blanks and on the other side of such blanks for little finger interfitting. The extent of this interfitting, say from a width of cloth for a determined size of glove, permits such a degree of saving 60 that blanks 19 for two finger backs may be additionally obtained from the transverse extent of such strip 1 of cloth. In practice this means that a narrower stock may be used or that from the same stock, due to this saving by permitting the two additional finger backs, economy of approximately three (3%) per cent in the transverse cutting is obtained.

In the progress of this group die longitudinally of the strips 1, such closeness of successive seating may occur by the departure from full form for one side of the portion 4 that longitudinal alignment may be maintained, with maintenance of the transverse economy for the stock together with longitudinal economy due to the proximity of the successive transverse direct groupings. In practice, this runs from one (1%) to two (2%) per cent. It accordingly follows that 70 due to this grouping of blanks by deformation, there is economy in fabric, approximating five (5%) per cent saving with no detraction whatsoever from the glove size as determined were the savings not introduced 75 as herein disclosed.

Furthermore, these economies in fabric may extend to economy in stitching and thus reduce the labor and thread cost. The blank tips for the second, third, and fourth fingers, 7, 8, 9, may be terminally tacked by stitching 20, 21, 22, to the glove wear face 23 having such fingers say of leather. These tacked terminals not only are connected to the wear face, but also to the finger backs 95 19. The index finger 6, 10, in the assembly of the edge of the wear face 23 therewith, is provided with stitching 24 from its finger tip 25 to the wrist portion adjacent gauntlet 26.

Thumb back 27 is stitch assembled on the index finger side to both the thumb lining blank 4 as well as to thumb facing 28 by stitch 29. Supplemental thereon, facing piece 30 has stitching 31 through thumb back 27. This facing 30 is, at its palm edge, assembled by stitching 32 with the palm lining and facing 23 up to the thumb crotch, and the thumb has upward therefrom an assembly stitching for the thumb back 27, the thumb wear facing strip 30 and the thumb facing 28, thus leaving the side of the thumb lining 4, toward the palm and of less than full form, loose along this stitching 32, but terminally tacked with the thumb by stitching 29.

Stitching 33 over the several fingers and down the finger sides, assembles merely the finger backs to the finger facings, thus leaving the linings 6, 7, 8, 9, only terminally tacked. This stitching 33 in the region of the wrist portions 18 assembles the lining at such point with the wear facing 23 and the finger back 19. This leaves the little finger lining 9 terminally tacked and free to the finger crotch toward the third finger and free to a point past the palm adjacent the wrist on the outer side or in the region 16 of the blank. The lining is accordingly held by the tacked portions in position to space the fingers and palm of the wearer from the wear facing of the palm and finger lining of the glove, with avoidance of hardness of stock and difficulty in stitching, not only between the fingers and along the side of the thumb toward the palm, but also along the palm toward the little finger.

This avoidance of hardness from stitching the linings with the other stock, leaves the glove more flexible, in no way detracts from the utility or the life of the glove, but really is a contributing factor toward longer life with economy in cutting therefrom.

What is claimed and it is desired to secure by Letters Patent is:

1. A palm and finger blank having a thumb portion with its tip of full form on one side only protruding from the wrist portion of the palm, whereby in progressing blank outlines successively along the material, finger portion tips may more closely approach the wrist region of an adjacent outline.

2. A palm and finger blank for gloves having integral therewith a wristwardly extending thumb portion and laterally an index finger back wider at the base than at the tip and abruptly narrowed into the palm and gradually tapering outward wristwardly, said blank at the base of the little finger being abruptly narrowed into the palm portion for a length equal to the little finger and abruptly widened at the wrist.

In witness whereof I affix my signature.
MELVIN MCKINLEY.
